UNITED STATES PATENT OFFICE

JOHAN PEHRSSON, OF ELYRIA, OHIO, ASSIGNOR TO THE COLSON COMPANY, OF ELYRIA, OHIO, A CORPORATION OF OHIO

MOP WRINGER

Application filed May 24, 1930. Serial No. 455,421.

This invention relates to mop wringers.

It is one of the objects of this invention to provide a mop wringer adapted to be mounted on a scrubbing pail, scrubbing tank or the like in an improved manner.

It is another object to provide a mop wringer which may be operated by one hand of the operator in an improved manner leaving his other hand free to manipulate the mop.

It is another object to provide a mop wringer which will be easy to operate and efficient in action.

Another is to provide a mop wringer in which the moving parts effecting the wringing or squeezing of the mop may be disposed in their normal position so as not to interfere with placing the mop in the wringer or removing it therefrom.

It is another object of my invention to provide an improved mop wringer of the type in which the mop is squeezed between two squeezing elements having relative bodily movement one toward the other.

It is another object to provide a mop wringer in which the maximum of squeezing pressure may be obtained with the minimum of effort on the part of the operator.

It is another object to provide a mop wringer in which the parts after use automatically return to a normal position permitting easy insertion of a mop in the wringer upon the next occasion of its use.

Another object is to provide a mop wringer of the class referred to which will be cheap and simple to manufacture and assemble and which admits of being formed largely from parts which may be stamped from sheet metal.

Other objects will be apparent to those skilled in the art to which my invention appertains.

My invention is fully disclosed in the following description taken in connection with the accompanying drawings, in which:

Fig. 1 is a side elevational view of an embodiment of my invention and with parts of a scrubbing pail and a mop indicated as associated therewith.

Fig. 2 is an elevational view taken approximately from the plane 2 of Fig. 1.

Fig. 3 is a top plan view of the parts shown in Fig. 1.

Fig. 4 is a cross-sectional view taken approximately from the plane 4 of Fig. 2.

Referring to the drawings, I have shown a mop wringer frame comprising side frame elements 1—1 preferably formed from relatively heavy sheet metal. A basket 3 formed from sheet metal and comprising a perforated bottom 4, a perforated front wall 5, and a perforated back wall 6 is disposed between the frame elements 1—1. The basket 3 is preferably not provided with side walls, but is formed from a flat sheet by bending the front and back walls at a right angle to the plane of the bottom. The lateral or side edges of the front, bottom and back portions of the basket thus formed abut upon the inner faces of the frame elements 1—1. A plurality of tie bolts 2—2 extend through suitable perforations in the frame elements 1—1, and by means of threads and nuts on the extreme ends thereof, the side frame elements 1—1 may be drawn into rigid engagement with the side edges of the basket 3 above described to clamp the same therebetween.

The frame elements 1—1 thus constitute side walls for the basket 3 and may be perforated as indicated at 7—7. The upper edges of the front wall 5 and back walls 6 of the basket are preferably turned or folded over two of the tie rods 2—2 as at 40—40 disposed adjacent the said upper edges of the basket, to position and help support the basket, and to give it a finished rounded edge. Strips 8 and 9 may be secured to the inner faces of the frame elements 1—1 under the basket bottom 4 and behind the basket back wall 6 respectively to help support the basket. The front edge of the frame elements 1—1 may also be bent inwardly as at 10—10 to engage the front wall of the basket to further position and support it.

Thus by means of the tie bolts 2—2, the basket 3 is tightly clamped between the frame elements 1—1, and the frame elements are suitably spaced apart thereby; and the basket

3 is rigidly supported on the frame elements 1—1.

The perforations in the front, back and bottom walls of the basket 3, for example, the 5 perforations 41 in the front wall and the perforations 7 in the frame elements 1—1 may be of any suitable size and suitably spaced. Preferably in the basket I employ perforations about one-fourth inch in diameter and 10 on five-eighths inch centers and in the heavier frame elements 1—1 I provide perforations preferably three-eighths inch in diameter and on five-eighths inch centers but these dimensions form no essential part of 15 my invention. To further stiffen and strengthen the structure, the top edges of the frame elements 1—1 may be bent over at an angle to form flanges 12—12.

In their rear portions, the frame elements 20 1—1 are formed to provide depending fingers 13—13 thus providing substantially vertical slots 14—14 between the fingers 13—13 and the frame elements 1—1, the slots being adapted to be telescoped or straddled over the 25 wall of a scrubbing pail or scrubbing tank to support the mop wringer thereon as indicated in the drawings where I have shown in broken lines at 15 a scrubbing pail. The frame elements 1—1 extend below the basket 3 and 30 may be connected together to stiffen them and to aid in positioning the wringer in the pail by a rearwardly convexly curved band of sheet metal 16, the ends 17 of which are bent into parallelism with the frame elements 1—1 35 and bolted or riveted thereto as at 18.

The frame elements 1—1 are provided with aligned guideways or grooves or slots therein 19—19 comprising vertical portions 20 extending from a point adjacent the bottom 4 40 of the basket 3 to a point adjacent its top and then turning into approximately horizontal portions 21—21 the vertical and horizontal portions being connected by a curved portion 22 of relatively large radius.

45 A presser foot is indicated generally at 23 formed from sheet metal and comprising a generally rectangular planular face portion 24, generally triangular sides 25, and a stiffening front edge portion 26, the sides 25 50 being disposed adjacent the frame elements 1—1 and bent at approximately right angles to the face 24 and the edge 26 being bent at an angle to the face 24. A stub shaft 27 extends through the walls 25 of the foot by means of suitable perforations therein and extends outwardly from the sides 25 and into the grooves 19—19 in the side frame elements 1—1, and the shaft 27 is rigidly secured to 55 the foot 23 by a rivet 28 passing through the shaft at approximately its middle and through the face portion 24 of the foot. Another shaft 29 extends through the walls 25 of the foot 23 and is parallel to and is spaced from the shaft 27 and extends into and through 60 65

the grooves or slots 19 in the frame elements 1—1.

A handle shaft 30 extends through suitable bearing perforations in the frame elements 1—1 and projects laterally from the frame elements on each side. At one end the shaft 30 has rigidly connected thereto a cam element 31 formed from a piece of relatively heavy sheet metal and provided with an arcuate or other curved slot or groove 32, the curvature being convex rearwardly and the slot 32 being adapted to embrace one end of the shaft 29. The cam element 31 has an extension 34 thereon to which a handle 35 may be secured.

The other end of the shaft 30 has rigidly secured thereon a cam element 36 which may be identical with the cam element 31 except that it is not provided with the extension 34. The two cam elements 31 and 36 are rigidly secured on opposite ends of the shaft 30, the shaft extending through suitable perforations therein and nuts 37 clamping the cam elements on the shaft. If desired, the cam elements 31 and 36 may be keyed to the shaft 30. The ends of the shaft 29 project through the curved cam slots 32 of the cam elements 31 and 36. Washers or spool heads 38 may be disposed on the shaft 29 on each side of the cam elements 31 and 36 retained by nuts 38. With the parts constructed as above described, the handle 35 may be moved to rock the cam element 31 around the axis of the shaft 30 and rock the shaft and the other cam element 36 rigidly connected to it. This movement of the cam elements 31 is communicated to the shaft 29 by the cam slots 32 and the shaft 29 being constrained to move only in the slots 19, is propelled therein. With the parts in the position shown in Fig. 1, the shaft 29 is first propelled toward the left in the horizontal portion 21 of the slot 19 and then around the curved portion 22 and then downwardly in the vertical portion 20, in the latter position the parts being as shown in Fig. 4. The movement of the shaft 29 carries the foot 23 with it and causes the shaft 27 to also travel in the slot 19.

The traveling movement of the two shafts 29 and 27 mounted in the foot 23 carries the foot with them and because of the shape of the slot 19 causes the foot 23 to move from the position shown in Fig. 1 to the position shown in Fig. 4. By means of the curvature of the cam slots 32, the rotational movement of the cam elements 31 and 36 may be made relatively rapid and the vertical downward movement of the foot 23 relatively slow whereby a leverage is obtained by which the foot 23 may be forced downwardly with great force or application of a relatively small force to the cam elements 31 and 36 by the handle 35.

Also, the farther the cam elements are rocked the greater the leverage becomes due

to the decreasing distance between the shaft 30 and the shaft 29. As will be understood, the maximum leverage is obtained by disposing the shaft 30 relatively near to the vertical portion 20 of the slot 19.

The vertical portion 20 of the slot 19 is so disposed relative to the rear wall of the basket 3 and the shafts 29 and 27 are so disposed relatively to the face 24 of the foot that the foot 23 may move downwardly into the basket 3. And as will now be understood, a mop indicated generally in broken lines at 39, placed in the basket 3 by means of a handle 42 thereon, may be compressed between the face portion 24 of the foot 23 and the walls of the basket 3 and water therein squeezed out and drained away through the perforations in the basket and in the frame elements 1-1.

20 Preferably I provide a spring 45 to return the handle 35 and the foot 23 to the positions shown in Fig. 1. The spring 45 is preferably of helical type coiled about the shaft 30 and anchored at one end to the shaft and at the other end anchored to an adjacent frame element 1.

As shown in Fig. 4, the face 24 of the foot 23 is of smaller dimension from rear to front of the basket 3 than the corresponding dimension of the basket so that a space is left between the reinforcing flange 26 and the front wall 5 of the basket to accommodate the body of the mop. And the flange 26 provides a smooth corner as at 46 for engagement with the mop. In lateral directions, the foot 23 may substantially fill the basket 3.

By providing the convexly curved element 16 connecting the side frames 1-1 and projecting rearwardly therefrom, the wringer as a whole is maintained in an up-right position in the pail by the engagement or abutment of the element 16 against the inner wall of the pail, and being of large area and convexly curved, all liability of denting or injuring the wall of the pail is prevented.

By curving the cam slots 32 so that they are concave inwardly and downwardly in the operation of the wringer, the camming surface of the slot may be presented to the ends of the shaft 29 more nearly normal to the direction of movement of the shaft than would obtain, for example, with a straight slot.

55 My invention is not limited however to the exact details shown and described inasmuch as many departures may be made therefrom without departing from the spirit of my invention or sacrificing its advantages.

60 I claim:

1. In a mop wringer, a frame, a mop receptacle comprising side and bottom walls provided with perforations, a pair of similar aligned L-shaped guide slots in opposite walls of the receptacle, a presser foot adapted to

be moved in the receptacle toward and from the bottom wall and out of the receptacle, a pair of guides on the presser foot extending therefrom and engaging each guideway to guide the said movement of the presser foot in the receptacle and for disposing the presser foot laterally of the receptacle when moved therefrom, one of the pair of guides extending outwardly through a said slot, a lever rotatably mounted on the frame, a cam portion on the lever provided with a camming surface engaging the said guide extending through the slot to move the presser foot upon rotation of the lever.

2. In a mop wringer, a frame, a mop receptacle comprising side and bottom walls, provided with perforations, a pair of similar aligned L-shaped guide slots in opposite walls of the receptacle, a presser foot adapted to be moved in the receptacle toward and from the bottom wall and out of the receptacle, two pairs of guides on the presser foot extending therefrom and one of the guides of each pair extending outwardly through a said L-shaped slot, to guide the said movement of the presser foot in the receptacle and for disposing the presser foot laterally of the receptacle when moved therefrom, a lever rotatably mounted on the frame, a pair of cams connected with the lever and movable thereby, the cams being provided with cam surfaces, engaging the said guides extending through the slots.

3. In a mop wringer, a frame, a mop receptacle comprising side and bottom walls provided with perforations, a pair of similar aligned L-shaped guideways in opposite walls of the receptacle, a presser foot adapted to be moved in the receptacle toward and from the bottom wall and out of the receptacle, a pair of shafts secured to the presser foot, extending laterally therefrom and into said slots for guiding the said movement of the presser foot in the receptacle and for disposing the presser foot laterally of the receptacle when moved therefrom, one of said shafts extending at each end thereof through the said slots, a lever shaft rotatably mounted on the frame, a lever for rotating the lever shaft, a pair of cams on the lever shaft rotatable therewith and a cam groove on each cam for engaging the ends of said shaft projecting through the slots to move the presser foot upon movement of the lever.

4. In a mop wringer, a frame, a mop receptacle comprising side and bottom walls provided with perforations, a presser foot adapted to be moved in the receptacle toward and from the bottom wall and out of the receptacle the foot having a mop pressing face adapted to be disposed substantially parallel to the receptacle bottom when in the receptacle and adapted to be disposed laterally of the receptacle and substantially at right angles to the bottom when out of the

- receptacle, the said pressing face being of such shape and size as to substantially fill the receptacle transversely thereof except for a clearance space adjacent one side wall of the receptacle proportioned to the transverse dimensions of a mop head, a lever pivotally mounted on the frame and means connecting the lever and the presser foot for transmitting to the foot said movements.
10. 5. In a mop wringer, a frame comprising a pair of spaced side frame members, a mop receptacle comprising side and bottom walls provided with perforations, a pair of similar aligned L-shaped guideways in the side frame members, a presser foot adapted to be moved in the receptacle toward and from the bottom wall and out of the receptacle, a pair of shafts mounted on the presser foot and provided with end portions extending through the slots to guide the said movement of the presser foot in the receptacle and for disposing the presser foot laterally of the receptacle when moved therefrom, a lever shaft rotatably mounted on the side frame members, and disposed adjacent a wall of the receptacle externally thereof, a lever connected to the lever shaft, a pair of cams on the lever shaft provided with curved cam slots engaging the ends of one of said shafts, the said slots being so disposed that the said shafts lie adjacent the said wall of the receptacle and internally of the receptacle during movement of the presser foot in the receptacle and the said cam slots moving the presser foot with an increasing lever ratio during movement of the presser foot toward the receptacle bottom.
6. In a mop wringer, a frame, a mop receptacle comprising side and bottom walls, at least one of said walls provided with perforations, a pair of similar aligned L-shaped guideways in opposite walls of the receptacle, a presser foot adapted to be moved in the receptacle toward and from the bottom wall and out of the receptacle, a pair of guides on the presser foot extending therefrom and engaging each guideway to guide the said movement of the presser foot in the receptacle and for disposing the presser foot laterally of the receptacle when moved therefrom, a lever rotatably mounted on the frame, and a cam portion on the lever adapted to engage the presser foot to move the same upon rotation of the lever.
55. 7. In a mop wringer, a frame, a mop receptacle comprising side and bottom walls, at least one of said walls provided with perforations, a presser foot adapted to be moved in the receptacle toward and from the bottom wall and out of the receptacle, and cooperating guide means associated with said presser foot and the said side walls to guide the said movement of the presser foot in the receptacle and for disposing the presser foot laterally of the receptacle when moved there-

from, a lever rotatably mounted on the frame, and a cam portion on the lever adapted to engage the presser foot to move the same upon rotation of the lever.

In testimony whereof I hereunto affix my ⁷⁰ signature this 22nd day of May, 1930.

JOHAN PEHRSSON.
